UNITED STATES PATENT OFFICE.

EMILY ANNA HAVENS, OF WHITE PLAINS, NEW YORK.

SKIRT-MARKER.

1,077,068.

Specification of Letters Patent.

Patented Oct. 28, 1913.

Application filed February 12, 1913. Serial No. 747,868.

To all whom it may concern:

Be it known that I, EMILY A. HAVENS, a citizen of the United States, and a resident of White Plains, in the county of Westchester and State of New York, have invented a new and Improved Skirt-Marker, of which the following is a full, clear, and exact description.

This invention relates to measuring instruments and has special reference to appliances for use by dressmakers or others for determining the proper length or swing of a skirt.

Among the objects of the invention is to simplify and improve this class of devices whereby the device may be accurately adjusted according to the length of the skirt desired, and when so adjusted will remain in a fixed position until the operation is completed.

A further object of the invention is to improve the general construction whereby the several parts of the apparatus may be folded into a small compass when not in use and therefore may be conveniently carried or packed away.

The foregoing and other objects of the invention will hereinafter be more fully described and claimed and illustrated in the drawings forming a part of this specification in which like characters of reference indicate corresponding parts in all the views, and in which—

Figure 1 is a perspective view of the device indicating its position when in use; Fig. 2 is a bottom plan view of the same; Fig. 3 is a partial plan view; and Fig. 4 is a vertical section substantially on the line 4—4 of Fig. 1.

The several parts of the device may be made of any suitable materials, and the relative sizes and proportions thereof may be varied to a considerable extent without departing from the spirit of the invention hereinafter claimed.

Referring more particularly to the drawings, the device includes a base comprising a plate 10 shown in the form of a disk upon which the person whose skirt is being fitted is supposed to stand. A pair of horizontal bars 11 are pivoted together preferably at the center of the plate 10 by means of a pivot 12. To the outer ends of the bars 11 are hinged as many gages 13 which are adapted to project vertically when in use or which may be swung around so as to fold

upon the respective bars when the device is out of use. Said gages are preferably provided with graduations extending from the floor upwardly so as to indicate the desired clearance between the skirt and the floor. An annulus 14 of a size to be conveniently received within the bottom of the skirt is adjustable vertically along and adapted to be secured to said gages 13. Any suitable means may be employed coöperating between the annulus and the gages for the purpose of so clamping the annulus in elevated position. As shown, I provide the annulus with a series of slots 15 through which the several gages extend, and adjacent each slot is a clamp comprising fixed members 16 and 17 and a set screw 18 operative through the member 17, forcing the gage snugly against the opposite member 16. Each gage 13 resting squarely upon the floor at one end and the annulus secured to the gage at a definite elevation will insure that with the annulus adjusted to all of the gages alike, the length of the skirt will be accurately determined. It will be noted, furthermore, that with the person being fitted standing upon the plate 10, it will be impossible for any part of the device to be tilted or otherwise thrown out of proper position while the operation is being made.

The person occupying the position indicated, the skirt to be fitted having been attached properly at the waistline will be draped down upon the outside of the annulus 14. Any person, then, either skilled or unskilled in the dressmaking art, will mark upon the skirt by a piece of chalk, the rim of the annulus which will indicate the height of the skirt desired. The skirt may then be turned up and finished in an obvious manner according to the chalk mark.

The annulus may be made of one piece or it may be hinged as indicated at 19 so that it may be folded into substantially one-half the size it would occupy if unitary. The plate 10 may have any desired relation on its lower surface to the bars 11 with respect to locking them in fixed position when the device is in operation; that is to say, the said bars may swing freely around the central pivot 12 so as to bring them into approximately parallel relation to each other for storage purposes, but to increase the stability of the device when in use I provide the plate with recesses 20 which will receive the bars snugly and prevent

rotation of any part when the plate is being stood upon. In order to provide, therefore, for the desired rotation, the pivot 12 may be long enough to provide sufficient looseness to allow the bars to swing clear of the recesses 20.

Having thus described my invention, I claim as new and desire to secure by Letters Patent:—

- 10 1. In a skirt marker, the combination of a base including a plurality of horizontal bars, a series of gages hinged to the outer ends of the bars, said gages being adapted to extend vertically from the bars or to be 15 swung around and folded upon said bars, an annulus coöoperating with said gages when the gages are vertical, and means to adjustably secure the annulus in fixed position with respect to the several gages.
- 20 2. In a skirt marker, the combination of

a base comprising a plate and a plurality of bars pivoted together and to said plate, said bars extending horizontally outward from said plate, a series of gages extending upwardly from the outer ends of said bars, 25 said bars and gages being adapted to swing around the center of the plate for storage purposes, a skirt engaging annulus adjustable vertically along said gages, and a series of clamps adapted to secure the annulus 30 at the desired elevation with respect to the base.

In testimony whereof I have signed my name to this specification in the presence of two subscribing witnesses.

EMILY ANNA HAVENS.
